(57) **CLAIM**

The ornamental design for a portable refrigerant container, as shown and described.

DESCRIPTION

FIG. 1 is a perspective view of a portable refrigerant container showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is an alternate perspective view thereof showing the portable refrigerant container before refrigerant is filled; and,

FIG. 9 is another alternate perspective view thereof showing the portable refrigerant container after refrigerant has been filled.
